UNITED STATES PATENT OFFICE.

EDWARD H. HART, OF NEW YORK, N. Y.

SUPPORTING-BANDAGE.

SPECIFICATION forming part of Letters Patent No. 349,793, dated September 28, 1886.

Application filed January 20, 1886. Serial No. 189,132. (No model.)

To all whom it may concern:

Be it known that I, EDWARD H. HART, of New York city, county and State of New York, have invented an Improved Supporting-Bandage, of which the following is a clear and exact description, reference being had to the accompanying drawings.

Figure 1 is a side view of my improved supporting-bandage; Fig. 2, a longitudinal section of the bandage. Fig. 3 is a detailed side view of the bag thereof. Fig. 4 is an end or face view of the same.

This invention relates to a supporting-bandage of the class described in Letters Patent No. 265,672 of October 10, 1882.

It consists in providing the bandage with a separate ring which is elastically connected to the bandage and to which the bag may be buttoned; also in the use of an elastic frilling for the support of the testicles, and in the use of another elastic frilling, all as herein-after more fully described.

In the drawings, A is the belt or bandage proper. B is a ring of elastic or flexible fabric, which is, by preferably elastic threads *a a*, connected with the bandage A. These threads pass through eyes *ff*, that are secured to the bandage. The ring B has buttons *bb* or analogous holders for securing to it the open end of the bag C. The bag C has button-holes *dd* to receive the buttons.

Behind the ring B are secured to the bandage A the ends of an elastic band or frilling, D, which is to support the testicles. Another similar elastic band, E, extends under the penis behind the ring B. This band E carries two of the eyes, *f'f'*, through which the

elastic threads *a*, that hold the lower part of the ring B, pass to the bandage.

The ring B, combined with the detachable bag C, permits the latter to be easily cleaned, and serves, moreover, when used without the bag, as a useful support in many cases. The semi-annular frilling D serves to support the parts mentioned without unduly inclosing them, and the band E serves to sustain the penis in position in the ring B.

I claim—

1. The bandage A, combined, by the elastic threads *a a*, with the open ring B, substantially as herein shown and described. 50

2. The bandage A, connected with the ring B, having fasteners *b*, and combined with the detachable bag C, substantially as herein shown and described. 55

3. The bandage A, combined with the elastic threads *a a*, open ring B, fasteners *b*, and detachable bag C, substantially as herein shown and described.

4. The bandage A, provided with the lower semi-annular elastic frilling, D, substantially as and for the purpose herein shown and described. 60

5. The bandage A, provided with the elastic frilling D, and with the elastic frilling E, 65 as specified.

6. The bandage A, combined with the elastic threads *a a*, open ring B, and elastic frillings D and E, substantially as herein shown and described.

EDWARD H. HART.
